UNITED STATES PATENT OFFICE.

THOMAS J. MOORE, OF MCLEAN COUNTY, ILLINOIS.

GATE-LATCHING MECHANISM.

Application filed May 6, 1925. Serial No. 28,392.

My invention relates to latching mechanism for gates, and more particularly to gates of the heavy or so-called stock enclosing type.

5 The object of my invention is in the provision of special gate latching mechanism fashioned in such manner as to be readily assembled upon any ordinary post member.

Another object of my invention is in the 10 provision of a gate latching mechanism fashioned in a manner to prevent any accidental opening of a gate member by stock enclosed within the field wherein the gate is used.

15 Still another object of my invention is in the provision of gate latching mechanism that is locked automatically by the movement of the gate and prevented from becoming unlocked except by the movement 20 of release portions thereof.

Yet another object of my invention is in the provision of an adjustable gate latch keeper that is adapted to permit the latching of the gate member upon either side of 25 the gate post when such movement is desired.

A further object of my invention is in the provision of a special gate latching mechanism for use upon gates used in stock 30 closures, said latching mechanism being fashioned to become automatically latched by movement of the gate, but having the release mechanism thereof located in a manner to prevent possible opening thereof by the accidental movement thereagainst of the 35 stock.

Other objects of my invention will appear in the following specification, taken in connection with the enclosed drawings, in 40 which—

Fig. 1 is a plan view of my gate latching mechanism, as applied to an ordinary barbed wire fence, although it is obvious that such mechanism might well be applied to any of 45 the well known types of fence;

Fig. 2 is a side elevation of my gate latching mechanism, showing its application to a formal gate member;

Fig. 3 is a perspective showing in detail 50 the mounting of my gate latch, and

Fig. 4 is a front elevation showing in detail the adjustable latch receiving portion.

Referring to the drawings, wherein I have 55 shown my gate lock applied upon a formal wooden gate member of the type usually used

in the enclosure for stock, I might add that such other gate or other type of fence as desired might be used and my particular gate latching device applied thereto by slight 60 mechanical adjustment or change.

In the present instance, the post member 10 is shown, of wood. Mounted upon this post 10, or rather bolted thereto, is the adjustable latch receiving portion, the same being made up of two brackets 12 and 13 65 that are adapted to be supported upon the post, either by bolting entirely through the post, as shown at 14, or exteriorly of the post, as shown at 15. If the post 10 is made of cement, then the bolt member 14 would 70 not be passed entirely through the same, but would be placed adjacent the front side of the post. In other words, it is obvious from the above that any expedient manner of bolting the bracket members 12 and 13 to the 75 post may be utilized. As shown perhaps most clearly in Figs. 3 and 4, the forward ends of the brackets 12 and 13 overlie each other in a slidably manner, as shown at 16, and are positively held in such position by 80 means of the bolt members 17 with appropriate washers and nuts. This front face portion 16 which is made up of the projecting forward ends of the brackets 12 and 13, is indented as at 18 and 19 in a manner to 85 provide receiving slots for the latch bar 20. This latch bar 20 has its outer end pivoted as at 21 upon an arm 22 pivoted as at 23 upon the pivoted gate member described generally as A. Means is provided normally for preventing the withdrawal of the latch bar 20 90 to the dotted line position shown in both Figs. 2 and 3, and said means comprises a hook 24, pivoted as at 25 to an adjacent portion of the gate, said hook being adapted to 95 catch in the manner shown in Fig. 3, a lug 26 upon the bar 22. From the above it may be seen that complete withdrawal of the latch bar is prevented except by first releasing the hook member 24. Reasons for the above 100 mounting of the latch member will be described later, following the complete description of the gate latching mechanism.

An automatic safety member 27 is bolted or pinned at 28 in a pivotal manner to the 105 post 10, said automatic safety member comprising a downwardly extending weighted portion 29 and the two oppositely projecting wing portions 30 and 31. This automatic safety mechanism might well be described as 110
